TYPE-WRITING MACHINE.

1,213,416.

Specification of Letters Patent.

Patented Jan. 23, 1917.

Application filed August 6, 1915. Serial No. 43,908.

To all whom it may concern:

Be it known that I, FRANK A. ROBINSON, a citizen of the United States, residing in Brooklyn borough, in the county of Kings, city and State of New York, have invented certain new and useful Improvements in Type-Writing Machines, of which the following is a specification.

The present invention relates to paper-feeding and associated mechanism for type-writing machines, especially adapted for writing on superposed webs and paper of many plies interleaved with carbon sheets.

The invention is particularly designed for use in connection with a machine such as shown in United States Letters Patent 1,132,055, to Wernery & Smith, dated March 16, 1915; although in certain of its features it is applicable to other machines. The machine of the patent referred to is adapted to be used for writing on continuous webs, each composed of a series of printed forms, and usually folded to have many plies, so that, by the use of interleaved carbon sheets, many copies may be simultaneously made. As the form sections are written they are detached from the web and the web advanced for the writing of the next succeeding section thereof; the carbon sheets being at such times drawn back along the plies of the web from the written to the next un-written section thereof. To permit of free movement of the web for detachment of a section thereof and for repositioning the web and carbon sheets, the platen, after each section of the web is written, is shifted bodily to unwrap the web therefrom and to relieve the pressure of the feed rollers thereon. It is apparent that if the rollers which effect the primary feed of the web are rollers which feed by merely pressing the web against the platen, then, if the web is of appreciable thickness, there is liable, in some cases, to be slipping of the roller with respect to the platen, due to the uncertain grip of one or the other, particularly if the web is folded longitudinally. Furthermore, in a web of many plies, the different plies will have paths of travel of different diameters around the platen, and consequently there is liable to be in some cases a lagging or slipping, or a crimping of some of the plies of the web during the feed thereof.

The principal object of the present in-

vention is to provide a means for effecting a positive primary feed of the web around the rotating platen, such that all plies thereof are drawn to the printing line without slipping or creeping, and particularly without undue crimping or distortion of the web. 60

It is an object of the invention to adapt such feeding means to a machine in which the platen is shifted after the writing of each section of the web to release the web 65 for detaching a section thereof, and for re-positioning it for further writing.

In its preferred embodiment, for the purposes stated, the feeding means consists of a pair of opposed rollers held resiliently to 70 one another and positively driven from the line-space mechanism of the typewriting machine at the rotation of the platen. These rollers are geared together, and may be spaced away from the platen to permit 75 free passage of the web thereto. They are in geared connection with the platen, and all the gears are so proportioned with respect to each other, and to the diameters of the feed rolls and platen, that the rolls and 80 platen have substantially the same peripheral speed when feeding; thus avoiding trouble from crimping of the web at the rolls, or between the rolls and the platen.

In a machine of the general character of 85 that of the Wernery & Smith Patent 1,132,055, above referred to, the feed rollers may be mounted on the frame which swings the platen between printing and paper-releasing positions. The gear which in that 90 machine keeps the line-space mechanism in permanent driving connection with the platen may serve as the gear for driving one of the opposing feed rolls, and the shaft of that roll may be the axle around which the 95 platen swings. In this way one gear is made to accomplish a double purpose, and by means thereof the structure is much simplified. At the same time this use of the gear in question assures proper feed of the 100 rolls with respect to the platen.

A feature of the invention is the means by which the rolls are separated automatically to release the web, when the platen is shifted to permit the web to be unwrapped 105 therefrom. This roll-separating means, in its preferred form, comprises a pair of cams on that part of the platen frame which does not swing in the paper-releasing operation. The shaft of one of the rolls is brought 110

against these cams by the swing of the frame which carries the rolls and the platen, and the cams force it, along elongated bearings in the swinging frame, to separate the rolls against the action of the resilient means which tend to hold the rolls together. The rolls are finally brought to a position in which the space thus opened between them permits free movement of the web in a straight line from the web-supporting table.

Another feature of the invention is a means for separating the feed rollers to permit of adjustment of the web when it is not desired to swing the platen to release the carbon sheets and detach a web section. This means may consist of a lever or bail pivoted to the non-swinging platen frame, and adapted to be rocked against the shaft of that roll which, as just stated, has movement on elongated bearings. By pressing on the lever or bail, the feed rolls may thus be separated.

Other features and advantages will appear hereinafter.

Figure 1 is a perspective view of the invention applied to an Underwood typewriting machine, the parts being in position to permit writing upon a work-piece. Fig. 2 is a perspective detail view of certain of the parts shown in Fig. 1; other parts of Fig. 1 being removed for a clearer understanding of the parts shown. Fig. 3 is a top plan view of the feed rollers in their normal or printing position with respect to the platen and line-space mechanism. Fig. 4 is a view in left-hand side elevation, of the mechanism shown in Fig. 3; certain additional features being shown in co-operative relation thereto, and the parts being in printing position. Fig. 5 is a view similar to that of Fig. 4, except that the parts are in paper-releasing position. Fig. 6 is a view in left-hand side elevation, showing the platen, feed rolls, carbon sheet holder, and other web-guiding elements, with the web in place thereon, and all parts being in the position assumed when the web is to be positioned prior to being cut. Fig. 7 is an enlarged detail view in left side elevation, showing particularly the gearing between the platen and the feed rolls and certain other related parts. Fig. 8 is a view similar to that of Fig. 6, except that the parts are in printing position. Fig. 9 is a view in side elevation, of the right-hand end plate of the swinging platen frame, showing the bearings of the platen and feed-roll shafts therein, and the means by which the feed rolls may be separated for adjustment of the web.

Referring to the drawings, the platen 10 is fixed on the shaft 11 which is journaled in a frame mounted to swing on a shaft 12, 65 having bearings in the end plates 13 of the

usual platen frame. This pivoted frame consists of end plates or arms 14 and 15 loose on the shaft 12. The platen has its bearings in the plates 14 and 15. The frame is normally held in the Fig. 1 position. It 70 is swung from its normal or printing position to its web-releasing position, as shown in the patent to Wernery & Smith, 1,132,055, by means of an arm or handle 16 which is riveted at 17^a to the left-hand plate 14 of 75 the swinging frame. For locking the platen frame in printing position, the handle 16 carries a pin 16^a adapted to be engaged by a hook 17 pivotally mounted on a bracket 18 on the end plate 13 of the frame to 80 which the swinging frame is attached. A spring 19 engages the hook and the bracket to hold the hook in platen-locking position and to return it to such position when free to do so. The nose of the hook is shaped 85 at 20 to permit the pin 16^a to cam it backward until the pin can pass under the nose, thereby making the locking operation automatic when the platen frame is swung down, to normal position. A tooth 21 on the hook 90 may serve to determine the return throw and normal position of the platen, in conjunction with a pin or stop 23 on the right-hand end of carriage-piece 13 at the front thereof. When the right-hand plate 15 95 strikes the pin 23, the platen frame is definitely arrested.

To effect the line-space feed or rotation of the platen, there are provided the usual hand wheel 24 and ratchet wheel 25, both 100 fast to a short shaft 26, mounted to rotate in the left-hand end piece 13 of the carriage. In printing position, the shaft 26 is concentric with the platen shaft 11. As is common in Underwood typewriting machines, 105 the ratchet is actuated by a pawl 27 on a slide 28, engaged by one arm 29 of a line-space lever pivoted at 30 to the carriage frame and having another arm 31 which carries the finger-piece 32. A spring 33 returns the slide and pawl to normal position. A spring detent 34 engages the ratchet wheel 25 to hold the platen against displacement. The driving connection 110 between the shaft 26, whose axis is not changeable, and the platen shaft 11, which swings from one to another position, consists of gears 35, 36 and 37. The gear 35 is fast to the shaft 26; the gear 36 is fast to the platen shaft, and is of the same size and 115 number of teeth as gear 35; and the gear 37 is fast on the axle 12 around which the platen frame swings, and has a face of sufficient width simultaneously to mesh with gears 35 and 36. The driving connection 120 between the shaft 26 and platen is thus maintained in all positions of the platen.

In Patent 1,132,055, to Wernery & Smith, above referred to, it is shown that in the 125 operation of removing a printed length 130

from the web, and in re-adjusting the web for printing the next length, the platen is swung from printing position to a position away from the feed rolls, so that the web no longer wraps around the platen, but may be moved freely in substantially a straight line from back to front of the machine. When the platen is in this position, the carbon sheets between the plies or folds of the section of the web to be removed, are drawn back into the length or section of web next to be printed; and, after removal of a length of the web, and re-positioning of the web, the platen is returned to its normal position against the feed rolls. In the present case, the operation is the same, except that, instead of the feed rolls heretofore used, other feed rolls, presently to be described, are here employed.

20. The web is preferably in a single piece, fan-folded longitudinally, to provide for several copies when carbon sheets are interleaved with the folds. It may also be in a crosswise fan-folded condition before being fed into the machine to permit of compactness and convenience in handling, or it may be fed from a roll. It is fed into the machine over a bar 38 at the rear of a table 39, having side rails 40 to which the bar 38 is secured. These rails are connected at the front of the table by a bar or tie-rod 41 supported by arms 42 secured to the platen carriage, so that the table has letter-feed movement with the platen. The table frame is further braced by cross-bars 43 and 44, and on the cross-bar 43 is a roller 45 which rides on a rail 46 carried by a framework 47, secured to or forming part of the main frame of the machine, and which supports the table 39 at the rear thereof.

45. The web is led onto the table through a set of fingers 48, each of which (as shown in Fig. 6), protrudes into the web to guide and separate two adjacent plies thereof. The fingers are stepped up one above the other, and those on one side of the table are staggered with respect to those on the other side of the table to be in position to receive the oppositely-folded plies of the web. The 50 fingers 48 are secured, as by screws 49, to the table. From the guide fingers 48 the web is led to the carbon sheet holder 50. It has been stated that the web is folded longitudinally so that several copies may be made at a time by the use of carbon sheets interleaved with the plies of the web. These carbon sheets, as above stated, are thrown back from the written portions of the web onto the length thereof next to be written, 55 at the time the web is released and before it is cut. For permitting forward line-space feed of the carbon sheets with the web, and for withdrawing the carbon sheets from the written to the next unwritten section of the web, the holder is in the form of a carriage

to which the rear ends of the carbon sheets are attached. This carriage (see Figs. 1 and 6) consists of a rectangular plate 51 having depending end flanges 52 on each of which are mounted two rollers 53 adapted to ride on inturned lateral flanges 54 on the side rails 40 of the table. The line-space feed of the web around the platen with the carbon sheets clamped by the feed rolls between the folds thereof, causes the holder 50 to be drawn forward on the rails 40 during the printing operation. For drawing back the holder to re-position the carbon sheets on the web when a printed section of the web is removed, there is attached to the holder a cord 55 which passes over a pulley 56 secured to the rear bar 38, and is brought forward to a spring drum 56^a (see Fig. 6), which is journaled on a stub shaft 56^b carried by an arm 56^c attached to the table at the front thereof. The drum yields to permit the line-space feed of the carbon sheets, but when the platen is thrown up, as indicated in Fig. 6, and the pressure of the feed rolls thereon is thus relieved, the tension of the drum on the cord 55 causes the holder 50 to be thrown back until stopped at the rear of the table, and the carbon sheets to be slid back along the folds of the web to position for writing the next web section. This means for throwing the holder is not new with the present invention, nor is the holder itself. For securing the rear ends of the carbon sheets to the holder, the latter carries clips or fingers 57^b on stepped plates 57 on the ends of the holder. Alternate clips are secured to opposite ends of the holder, and are progressively stepped up (as in the case of the fingers 48 at the rear of the table), to assure proper spacing of 100 the web folds and movement of the carbon sheets between the same.

From the carbon holder 50 the web is led over a tie-rod 57^a on the carriage frame (see Fig. 8), down around the platen, and up 110 between the feed rolls 58 and 59, past the cutter 60 and onto the shelf 61. The shelf 61 is turned over at its ends to have flanges 62, which are riveted, as at 63, to the side plates 14 and 15 of the swinging platen frame, so that, as indicated in Fig. 6, the shelf may swing with the platen. The shelf carries the usual gage bar 64, with the gage piece 65 adjustable therealong, for measuring the lengths to be cut from the web. A 115 set screw, or thumb screw, 66 passes through the holding portion 67 of the gage piece and into contact with the bar 64 to provide for adjustable attachment of the gage piece to the bar. In measuring the lengths to be 120 cut from the web, the leading edge of the web, when the web is released by the swing of the platen (see Fig. 6), is drawn forward to the gage piece 65. The carbon sheets then being drawn back out of the advanced sec- 130

tion of the web, the latter is cut off by being drawn against the cutting blade 60.

That part of the apparatus shown in the drawings, and thus far described in detail, is not in itself new with the present invention, with the exception of the feed rolls 58 and 59. These rolls, it will be noted upon reference to Fig. 8, are the primary feed rolls for the web 70. Commonly the rolls which primarily control the feed of the web are rolls which effect the feed by pressing the web against the platen; and such rolls are usually, although not always, located below the platen. The purpose in so locating the rolls in the ordinary typewriting machines has been to assure a close wrapping of the paper around the platen before it reaches the printing line, so that, at the printing line, it must bear firmly on the platen without possibility of play. In a machine such as the present, however, the web back of the printing line is held tautly to the platen by the action of the spring drum on the carbon-sheet holder, and by reason of the turn of the web over the rod 41; the length and weight of the web and the friction exerted on it by the guides over and through which it passes. Pressure rolls back of the printing line are therefore not ordinarily required in connection with webs as here employed. As has heretofore been indicated, the web used in the present machine may have many folds with interleaved carbon sheets; and consequently a primary feed of the same by mere pressure against the platen is likely to result in a crimping, or lag or slip in the feed of the outer plies, because of the difference in diameter of the paths of movement of the several plies around the platen. It is for this reason that the feed rolls of the present invention have been adopted. These rolls 58 and 59 (see Fig. 8) bear, one on each side, on the web, thereby assuring uniform feed of all the plies of the web. In fact, the web is shown as having a turn, first to the right and then to the left, in its passage by the rolls 58 and 59, so that, with both rolls set near the platen, all the plies of the web may have paths of equal length through and around the feed rolls. Neither rolls 58 nor rolls 59 bear on the platen, as otherwise the difference in diameters of the feed rolls and platen would cause a differential feed of the parts of the web engaged by them. The feed rolls grip the web at a point removed from the platen, preferably, as near as may conveniently be, in a direct line from the printing point to the paper shelf 61. The rolls 58 and 59 are shown as of the same diameter so that, turning at the same speed, they give all the plies of the web a uniform feed. Instead of a single roll 58, there are preferably several rolls 58, all fixed to the shaft 12 on which the platen frame is loosely mounted. Similarly,

there are several rolls 59, all fixed to a shaft 71, which has bearing in the side plates 14 and 15 of the swinging platen frame. The rolls 58 are driven from the platen on line-space movement of the latter, and the rolls 59 are driven from the shaft of the rolls 58. This drive of the rolls 58 is effected by means of the gears 36 and 37 which, as will be recalled, also serve to effect the drive of the platen from the gear 35 of the line-space mechanism. The gears 36 and 37 are so proportioned as to pitch-diameter that, with the rolls 58 spaced from the platen, the peripheral speeds of the platen and rolls 58 are the same; this, as before stated, in order that there may be no differential feed or crimping of parts of the web. Since the rolls 58 are to be held away from the platen, although driven at the same peripheral speed as the latter, the pitch-diameter of the gear 36 is greater than that of the platen, according to the distance at which the rolls 58 are held. The drive of the rolls 59 is effected by means of a pinion 72, fast to the shaft 12, which meshes with a pinion 73 of like pitch-diameter and a number of teeth, fast to the shaft 71. The shaft 12 is held against longitudinal displacement by collars 12^a (see Fig. 3) secured to the shaft and abutting the plates 14 and 15. Shaft 71 is similarly held against longitudinal displacement by collars 71^a, also abutting the plates 14 and 15.

When the platen frame is swung from Fig. 4 position to Fig. 5 position, to release the web, the rolls 59 are separated from the rolls 58. In order that this separation may take place without disengagement and independent rotation of the gears 72 and 73, and that these gears may at all times move back to driving engagement without clashing or impedance, the teeth of these gears (see Fig. 7) are of such length that, even when the rolls 58 and 59 are separated (see Fig. 5), the gears remain intermeshed. To permit movement of the rolls 59 away from the rolls 58, the shaft 71, which carries the rolls 59, has bearing in slots 74 in the plates 14 and 15 of the swinging frame. Normally, that is to say, for printing, the shaft 71 is resiliently held in Fig. 7 position in the slots 74 by means of coil springs 75 (see Fig. 3), one near each end of the shaft 71, and which are looped over the shaft 71 at one of their ends and over the shaft 12, at their other ends. For separating the shafts 71 and 12 against the action of the springs 75, when the platen is swung to Fig. 5 position, there are two cams 76, one fast to each of the end pieces 13 of the frame in which the swinging frame is mounted, (see Fig. 3), just outside of the plates 14 and 15 of the swinging platen frame. The shaft 71 (see Fig. 3) extends outward beyond the cams 76, so that, in swinging the frame from Fig. 4 to Fig. 5 position, the shaft 71 strikes the

cams 76, and thereafter, on further movement of the swinging frame, the shaft 71 is forced to travel along the cams until the rolls are separated, as shown in Fig. 6, with the shaft 71 at the other ends of the slots 74 in which it has bearings. On return of the platen frame to printing position, the springs 75 return the shaft 71 with the rolls 59, to their Fig. 7 position.

10 It may be desired to adjust the web without releasing the carbon sheets or going through the operation of throwing the platen frame. For this purpose, provision is made for movement of the rolls 59 from the rolls 58, while the other parts remain in Fig. 7 position. This movement is accomplished by means of a bail comprising a cross bar 78 on arms 79; the arms 79 being pivoted, one at each side of the machine, as 20 at 80, to the adjacent plates 14 and 15 of the platen frame, and being adapted to be swung backwardly against the roll shaft 71 to move the latter, against the action of springs 75, to Fig. 9 position. A handle 81 attached to the bail may be used to throw the same; and the cutter shaft 82 may serve as a stop to limit this movement. On release of the handle 81, the springs 75 return the rolls 59 to normal Fig. 8 position.

30 The cutter blade 60 is mounted on the rock-shaft 82, and is held in normal (Fig. 1) position by means of a spring 83 secured to the shaft 82 and to the plate 14. A finger-piece 84 attached to the shaft 82 serves 35 as a means for throwing the cutter to the web when a section of the latter is to be removed. Upon release of the finger-piece, the spring 83 returns the cutter to normal position. Except for the position in which 40 the cutter is mounted, because of the feed rolls 58 and 59, it is not different from those heretofore in use.

Variations may be resorted to within the scope of the invention, and portions of the 45 improvements may be used without others.

Having thus described my invention, I claim:

1. In a typewriting machine, the combination with a rotary platen, of a pair of feed 50 rolls between which a work-piece may be grasped to be thereby drawn over the platen, and means for effecting a positive drive of said rolls and the platen at the same peripheral speed to cause the same to act when 55 in motion as the sole means for feeding the work-piece.

2. In a typewriting machine, the combination with a rotary platen, of a pair of feed 60 rolls between which a work-piece may be grasped to be thereby drawn over the platen, intermeshing gears, one fast to each of said rolls, for effecting a positive drive of said rolls at the same peripheral speed to cause the same to act as the primary means for 65 feeding the work-piece, and a gear fast to

the platen and intermeshing with one of said roll gears for effecting a drive of the roll gears and the platen in unison, said rolls acting when in motion as the sole means for feeding the work-piece.

3. In a typewriting machine, the combination with a platen, of a pair of feed rolls between which a work-piece may be grasped after it leaves the printing line, to be thereby drawn over the platen, means for effecting a positive drive of said rolls and said platen at the same peripheral speed to cause the same to act when in motion as the sole means for feeding the work-piece, and means for holding the work-piece to the 70 platen behind the printing line.

4. In a typewriting machine, the combination with a platen, of a pair of feed rolls between which a work-piece may be grasped to be thereby drawn over the platen, means 75 for effecting a positive drive of said rolls and said platen at the same peripheral speed to cause the same to act when in motion as the sole means for feeding the work-piece, and means for exerting a draw on the work-piece behind the printing line to hold the 80 same snugly against the platen.

5. In a typewriting machine, the combination with a platen, of a pair of feed rolls between which a work-piece may be grasped 95 to be thereby drawn over the platen, means for effecting a positive drive of said rolls and said platen at the same peripheral speed to cause the same to act when in motion as the sole means for feeding the work-piece, and a bar over which the work-piece is turned behind the printing line to cause the work-piece to be held snugly to the 100 platen as it approaches the printing line.

6. In a typewriting machine, the combination with a platen, of a pair of feed rolls between which a work-piece may be grasped to be thereby drawn over the platen, means for effecting a positive drive of said rolls and said platen to cause the same to act 105 when in motion as the sole means for feeding the work-piece, and resilient means for drawing on the work-piece behind the printing line to cause the work-piece to be held snugly to the platen as it approaches the 110 printing line.

7. In a typewriting machine, the combination with a platen, of a pair of feed rolls between which a work-piece may be grasped to be thereby drawn over the platen, means 115 for effecting a resilient pressure of one of said rolls on the other, and means for effecting a positive drive of said rolls and said platen at the same peripheral speed to cause the same to act when in motion as the sole 120 means for feeding the work-piece.

8. In a typewriting machine, the combination with a platen, of a pair of feed rolls between which a work-piece may be grasped to be thereby drawn over the platen, means 125

for effecting a resilient pressure of one or said rolls on the other, means for effecting a positive drive of said rolls and said platen at the same peripheral speed to cause the same to act when in motion as the sole means for feeding the work-piece, and means for relieving the pressure of one of said rolls on the other to release the work-piece.

9. In a typewriting machine, the combination with a rotary platen, of a pair of feed rolls between which a work-piece may be grasped to be thereby drawn over the platen, one of said rolls being shiftable to and from the other to engage or release the work-piece, and intermeshing gears fast to said rolls for effecting a drive of the same in unison, the teeth of said gears being of sufficient length to maintain the same in mesh when the rolls are shifted apart.

10. In a typewriting machine, the combination with a rotary platen, of a pair of feed rolls between which a work-piece may be grasped to be thereby drawn over the platen, one of said rolls having an elongated bearing over which it may be shifted to and from the other roll, to engage or release the work-piece, a spring tending to hold the rolls together, and means for shifting said shiftable roll on its elongated bearing.

11. In a typewriting machine, the combination with a rotary platen, of a pair of feed rolls between which a work-piece may be grasped to be thereby drawn over the platen, one of said rolls having an elongated bearing over which it may be shifted to and from the other roll, to engage or release the work-piece, a spring tending to hold the rolls together, means for shifting said shiftable roll on its elongated bearing, and intermeshing gears, one fast to each of said rolls for driving the same in unison, the teeth of said gears being of sufficient length to maintain the gears in mesh when the rolls are shifted apart.

12. In a typewriting machine, the combination with a rotary platen, of a pair of feed rolls between which a work-piece may be grasped to be thereby drawn over the platen, one of said rolls being shiftable to and from the other to engage or release the work-piece, intermeshing gears fast to said rolls for effecting a drive of the same in unison, the teeth of said gears being of sufficient length to maintain the same in mesh when the rolls are shifted apart, and a gear on the platen in permanent mesh with one of said roll gears for driving the rolls with the platen.

13. In a typewriting machine, the combination with a rotary platen, of a pair of rolls between which a web is grasped to be thereby drawn around the platen, means for leading the web to such part of the platen as to cause it normally to wrap the platen as it is drawn around the same, means for

swinging the platen to a position where the web is unwrapped and released therefrom, and means for swinging the rolls with the platen to provide a straight passage for the web through the machine.

14. In a typewriting machine, the combination with a rotary platen, of means for drawing a web to and around the platen, means for leading the web to such part of the platen as to cause it to wrap the platen as it is drawn around the same, means for shifting the platen to unwrap the web therefrom, said web-drawing means comprising a pair of rolls between which the web is grasped, and means for positively driving both of said rolls and the platen at the same peripheral speed.

15. In a typewriting machine, the combination with a rotary platen, of means for drawing a web to and around the platen, means for leading the web to such part of the platen as to cause it to wrap the platen as it is drawn around the same, means for shifting the platen to unwrap the web therefrom, said web-drawing means comprising a pair of rolls, gearing connecting said rolls with each other and with the platen, and means for positively driving said gearing.

16. In a typewriting machine, the combination with a rotary platen, of means for drawing a web to and around the platen, means for leading the web to such part of the platen as to cause it to wrap the platen as it is drawn around the same, means for shifting the platen to unwrap the web therefrom, said web-drawing means comprising a pair of rolls between which the web is grasped, and means for positively driving both of said rolls and the platen at the same peripheral speed, said rolls being out of engagement with the platen so as to leave an unrestricted passage for the web between said platen and said rolls.

17. In a typewriting machine, the combination with a rotary platen, of means for drawing a web to and around the platen, means for leading the web to such part of the platen as to cause it to wrap the platen as it is drawn around the same, means for shifting the platen to unwrap the web therefrom, said web-drawing means comprising a pair of rolls between which the web is grasped, a driving connection between the platen and one of said rolls, and a driving connection between said rolls, both of said driving connections being maintained when the platen is shifted.

18. In a typewriting machine, the combination with a rotary platen, of a pair of rolls between which a web is grasped to be thereby drawn to and around the platen, means for leading the web to such part of the platen as to cause it to wrap the platen as it is drawn around the same, means for swinging the platen around the axis of one

- of said rolls, to unwrap the web from the platen, and means for driving said rolls.
19. In a typewriting machine, the combination with a rotary platen, of a pair of rolls between which a web is grasped to be thereby drawn to and around the platen, means for leading the web to such part of the platen as to cause it to wrap the platen as it is drawn around the same, means for 5 swinging the platen around the axis of one of said rolls to unwrap the web from the platen, a gear on the roll around whose axis the platen swings, and a gear on the platen in mesh with said roll gear for effecting a drive of the rolls in unison with the platen.
20. In a typewriting machine, the combination with a rotary platen, of a pair of rolls between which a web is grasped to be thereby drawn to and around the platen, means for leading the web to such part of the platen as to cause it to wrap the platen as it is drawn around the same, means for 10 swinging the platen around the axis of one of said rolls to unwrap the web from the platen, a gear on the roll around whose axis the platen swings, and a gear on the platen in mesh with said roll gear for effecting a drive of the rolls in unison with the platen, said intermeshing gears being proportioned 15 to drive the rolls at the same peripheral speed as the platen with free passage for the web between the rolls and the platen.
21. In a typewriting machine, the combination with a rotary platen, of a pair of rolls between which a web is grasped to be thereby drawn to and around the platen, means for leading the web to such part of the platen as to cause it to wrap the platen as it is drawn around the same, means for 20 swinging the platen around the axis of one of said rolls to unwrap the web from the platen, means for driving said rolls, and means for separating said rolls when the platen is swung on said axis.
22. In a typewriting machine, the combination with a rotary platen, of a pair of rolls between which a web is grasped to be thereby drawn to and around the platen, means for leading the web to such part of the platen as to cause it to wrap the platen as it is drawn around the same, means for 25 swinging the platen around the axis of one of said rolls to unwrap the web from the platen, means for driving said rolls, and a cam against which one of said rolls is moved to separate it from the other roll when the platen is swung around said axis.
23. In a typewriting machine, the combination with a rotary platen, of a pair of rolls between which a web is grasped to be thereby drawn to and around the platen, means for leading the web to such part of the platen as to cause it to wrap the platen as it is drawn around the same, means for 30 swinging the platen around the axis of one of said rolls to unwrap the web from the platen.
24. In a typewriting machine, the combination with a rotary platen, of a pair of rolls between which a web is grasped to be thereby drawn around the platen, means for leading the web to such part of the platen as to cause it to wrap the platen as it is 35 drawn around the same, means for swinging the platen around the axis of one of said rolls to unwrap the web from the platen, means for driving said rolls, and a cam for separating said rolls when the platen is 40 swung around its axis.
25. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, and means for 45 swinging said frame to cause the web to be unwrapped from the platen.
26. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, means for 50 swinging said frame to cause the web to be unwrapped from the platen, and means for separating the rolls when the frame is 55 swung.
27. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, the axis of one 60 of said rolls being shiftable on said frame to and from the axis of the other roll, means for swinging the frame, and means acting, when the frame is swung, to move said shiftable axis with the roll thereon away from the other roll.
28. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, the axis of one of said rolls being shiftable on said frame to and from the axis of the other roll, means for swinging the frame, and means acting, when the frame is swung, to move said shiftable axis with the roll thereon away from the other roll.

web to such part of the platen as to cause it to wrap the platen as it is drawn around the same, a swinging frame in which the platen and said rolls are mounted, the axis of one of said rolls being shiftable on said frame to and from the axis of the other roll, means for swinging the frame, and a fixed cam against which said shiftable axis is drawn, when said frame is swung, to cause said rolls then to be separated.

29. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, the axis of one of said rolls being shiftable on said frame to and from the axis of the other roll, means for swinging the frame, a fixed cam against which said shiftable axis is drawn, when said frame is swung, to cause said rolls then to be separated, and resilient means for holding said rolls normally together and for bringing the same together on reverse swing of the frame.

30. In a typewriting machine, the combination with a rotary platen, of a pair of rolls between which a web is grasped to be thereby drawn around the platen, means for driving said rolls, means for leading the web to such part of the platen as to cause it to trap the platen as it is drawn around the same, a swinging frame in which the platen and said rolls are mounted, the axis of one of said rolls being shiftable on said frame to and from the axis of the other roll, means for swinging the frame, and an abutment against which said shiftable axis is drawn, when said frame is swung, to cause said rolls then to be separated.

31. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, the axis of one of said rolls projecting through and beyond slots in the end plates of said frame, means for swinging the frame, and fixed abutments in the path of the projecting ends of said axis to engage the latter and shift the same in said slots, thereby separating the rolls when the frame is swung.

32. In a typewriting machine, the combination with a rotary platen, of a pair of rolls between which a web is grasped to be thereby drawn around the platen, means for driving said rolls, means for leading the web to such part of the platen as to cause it to

wrap the platen as it is drawn around the same, a swinging frame in which the platen and said rolls are mounted, the axis of one of said rolls being shiftable on said frame to and from the axis of the other roll, means for swinging the frame, means acting, when the frame is swung, to move said shiftable axis with the roll thereon away from the other roll, and means for so shifting the rolls apart when the frame is not swung.

33. In a typewriting machine, the combination with a rotary platen, of a pair of rolls between which a web is grasped to be thereby drawn around the platen, means for driving said rolls, means for leading the web to such part of the platen as to cause it to wrap the platen as it is drawn around the same, a swinging frame in which the platen and said rolls are mounted, the axis of one of said rolls being shiftable on said frame to and from the axis of the other roll, means for swinging the frame, means acting, when the frame is swung, to move said shiftable axis with the roll thereon away from the other roll, and a lever pivoted to said frame for moving said shiftable axis with the roll thereon away from the other roll when said frame is not swung.

34. In a typewriting machine, the combination with a rotary platen, of means for drawing a web to and around the platen, means for leading the web to such part of the platen as to cause it to wrap the platen as it is drawn around the same, means for shifting the platen to unwrap the web therefrom, said web-drawing means comprising a pair of rolls between which the web is grasped, means for positively driving said rolls, and means for separating said rolls when the platen is shifted.

35. In a typewriting machine, the combination with a rotary platen, of means for drawing a web to and around the platen, means for leading the web to such part of the platen as to cause it to wrap the platen as it is drawn around the same, means for shifting the platen to unwrap the web therefrom, said web-drawing means comprising a pair of rolls between which the web is grasped, means for positively driving said rolls, and means for automatically separating said rolls when the platen is shifted.

36. In a typewriting machine, the combination with a rotary platen, of a pair of rolls between which a web is grasped to be thereby drawn around the platen, means for leading the web to such part of the platen as to cause it normally to wrap the platen as it is drawn around the same, means for shifting the platen to unwrap and release the web therefrom, and line-space mechanism for driving both of said rolls and the platen at the same peripheral speed when the latter is in normal position.

37. In a typewriting machine, the combination with a rotary platen, of a pair of rolls between which a web is grasped to be thereby drawn around the platen, means for leading the web to such part of the platen as to cause it normally to wrap the platen as it is drawn around the same, means for shifting the platen to unwrap and release the web therefrom, line-space mechanism 5 non-shiftable with the platen in the web-releasing operation, and gearing from the line-space mechanism to the platen and rolls.
38. In a typewriting machine, the combination with a rotary platen, of a pair of rolls between which a web is grasped to be thereby drawn around the platen, means for leading the web to such part of the platen as to cause it normally to wrap 10 the platen as it is drawn around the same, means for swinging the platen to unwrap and release the web, line-space mechanism non-shiftable with the platen in the web-releasing operation, a gear fast to the platen 15 and concentric therewith, a gear forming part of the line-space mechanism, said gears being concentric when the platen is in normal position, and a third gear fast to the shaft of one of said rolls, said third gear 20 acting as an intermediary between said other gears and as a means for driving said rolls from the line-space mechanism.
39. In a typewriting machine, the combination with a rotary platen, of a pair of rolls between which a web is grasped to be thereby drawn around the platen, means for leading the web to such part of the platen as to cause it normally to wrap the platen as it is drawn around the same, 25 means for swinging the platen to unwrap and release the web, line-space mechanism non-shiftable with the platen in the web-releasing operation, a gear fast to the platen and concentric therewith, a gear forming part of the line-space mechanism, said gears being concentric when the platen is in normal position, a third gear fast to the shaft 30 of the roll whose axis serves as the axis about which the platen is swung, said third gear intermeshing with both of said other gears, intermeshing gears in the shafts of the two rolls for effecting a positive drive of the two rolls in unison, and means for separating the rolls, without unmoving the intermeshed gears thereof, when the platen is swung to release the web.
40. In a typewriting machine, the combination with a rotary platen, of a pair of rolls between which a web is grasped to be thereby drawn around the platen, means for leading the web to such part of the platen as to cause it normally to wrap the platen as it is drawn around the same, 35 means for swinging the platen to unwrap and release the web, line-space mechanism non-shiftable with the platen in the web-releasing operation, a gear fast to the platen and concentric therewith, a gear forming part of the line-space mechanism, said gears being concentric when the platen is in normal position, and a third gear fast to the shaft of one of said rolls, said third gear intermeshing with both of said other gears, 40 and the shaft in which it is mounted being the axis around which the platen is swung between printing and web-releasing positions.
41. In a typewriting machine, the combination with a rotary platen, of a pair of rolls between which a web is grasped to be thereby drawn around the platen, means for leading the web to such part of the platen as to cause it normally to wrap the platen as it is drawn around the same, means for swinging the platen to unwrap and release the web, line-space mechanism non-shiftable with the platen in the web-releasing operation, a gear fast to the platen and concentric therewith, a gear forming part of the line-space mechanism, said gears being concentric when the platen is in normal position, a third gear fast to the shaft of the roll whose axis serves as the axis about which the platen is swung, said third gear intermeshing with both of said other gears, intermeshing gears in the shafts of the two rolls for effecting a positive drive of the two rolls in unison, and means for separating the rolls, without unmoving the intermeshed gears thereof, when the platen is swung to release the web.
42. In a typewriting machine, the combination with a rotary platen, of a pair of rolls between which a web is grasped to be thereby drawn around the platen, means for leading the web to such part of the platen as to cause it normally to wrap the platen as it is drawn around the same, means for shifting the platen to unwrap and release the web therefrom, line-space mechanism, a gear driven by said mechanism on the shaft of one of said rolls, and a gear on the platen driven from said roll gear.
